UNITED STATES PATENT OFFICE

171,586

GOLF PRACTICE DEVICE

August C. Engh, Yorkville, Ill.

Application March 10, 1953, Serial No. 23,977

Term of patent 14 years

(Cl. D34—5)

To all whom it may concern:

Be it known that I, August C. Engh, a citizen of the United States, residing at Yorkville, State of Illinois, have invented a new, original, and ornamental Design for a Golf Practice Device, of which the following is a specification, reference being had to the accompanying drawings forming a part thereof.

Fig. 1 is a top plan view of a golf practice device, showing my new design;

Fig. 2 is a side elevational view thereof, looking at the left side of Fig. 1; and

Fig. 3 is a perspective view thereof.

The dominant features of my new design are shown in solid lines in the drawings.

I claim:

The ornamental design for a golf practice device, as shown and described.

AUGUST C. ENGH.
